Primary Examiner — Ryan Harvey

(74) Attorney, Agent, or Firm — Daniel M. Cohn;
Howard M. Cohn(57) **CLAIM**

The ornamental design for a UFO toy, as shown and described.

DESCRIPTION

FIG. 1 is a perspective view of a UFO toy showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;
FIG. 10 is an enlarged view of portion 10 shown in FIG. 1;
and,FIG. 11 is an enlarged view of portion 11 shown in FIG. 1.
The dash-dash broken lines in the drawings depict portions
of the UFO toy that form no part of the claimed design.**1 Claim, 11 Drawing Sheets**(56)
